UNITED STATES PATENT OFFICE

ULRICH KIRCHNER, OF BIBERACH-ON-THE-RISS, AND GERALD STRECKER, OF DARMSTADT, GERMANY

CYLINDER PAPER MILL

Application filed November 2, 1929, Serial No. 404,252, and in Germany November 14, 1928.

In spite of continuous experiments which have been made in the paper and pasteboard industry for more than 200 years for the purpose of replacing the cylinders which are generally used by machines operating at a lower consumption of power, more rapidly or continuously, none of these constructions have been capable of even only approximately replacing the cylinders. The conical 10 pulp mill, which constitutes an enlargement of the foundation over the entire surface of the cylinder grinding roller has only been capable of introduction in particular cases as it operates with too considerable 15 hardness. The bar mills which have been recently introduced in America, and also the conical or stone beating mills are only capable of use in very definite closely defined fields even though they show an improvement 20 as regards consumption of power and continuity of the grinding operation. The two main reasons why the cylinder machine in its present form requires improvement are the necessary charging operation required 25 therewith, and its relatively high consumption of power. Both defects are substantially due to the same reason.

If the path of the paper pulp in a cylinder machine is traced as one line, and there 30 is marked thereon the distance during which the grinding operation takes place, namely the ground work, it will be seen that this distance is only a very small proportion of the whole line. By passing the material once 35 through the machine the grinding is not completed, but on the contrary the material must be passed a number of times through the grinding point, that is to say, the operation must be carried out by repeated charging.

This illustration also indicates that the material, in order to return to this grinding position, must follow a long path. The 40 pulp, however, is a viscous mass, and in order to move over this path must have a considerable fall. Behind the grinding point it must, therefore, be pumped to a higher level in order to be able to return to the grinding position. This explains the second disadvantage of the cylinder machine, viz. its high

consumption of power. The material after each passage through the grinding point must be pumped to a higher level through a considerable distance which is generally effected by the grinding roller itself. The 55 necessary consumption of power for this purpose is already considerable and is further increased by reason of the fact that the grinding roller operates very poorly as a pump. 60

In combination with the foregoing a fundamental side of cylinder grinding will also be dealt with. The fact that the length of the grinding surface is very small relatively to the total path makes it necessary 65 for the material at the grinding point to be treated comparatively energetically, that is to say, it must be comminuted by sharp cuts. For felting the material it is necessary to comminute the material more by squeezing 70 than by cutting. The capacity for felting of the material increases when the treatment is carried out very slowly and carefully. If attempts are made to effect this in a cylinder machine, by effecting the grinding carefully, 75 then for the production of a unit of paper material such long periods of rotation and such high costs of power are incurred that the process becomes uneconomical.

Further it is, however, also important and 80 necessary for obtaining an efficient grinding action to allow the material, in addition to the suitable treatment of the grinding surfaces themselves, to remain alone during the period between its passage through the grinding points, as naturally the swelling actions 85 in the fibres and the formation of slime require time for their development.

In order to eliminate the above mentioned 90 drawbacks of the cylinder machine it is, therefore, necessary to improve the ratio between the length of the grinding surface and the total path of the pulp whilst retaining the change between the passage 95 through the grinding surfaces and the conveying between the grinding points so that in the meantime the material is left to itself.

According to the present invention this 100 double result is obtained in that in the interior of the grinding roller, which in the

known manner is made hollow and is open at its ends, there is provided a ground-work which only extends over a portion of the inner periphery of the grinding roller and that the latter is fitted on its inner side with grinding tools which may consist in the known manner of metal cutters or stone-ware.

The ground-work provided in the interior of the grinding roller is preferably suspended 10 by means of pivots on arms of a shaft extending through the grinding roller and capable of being raised and lowered relatively thereto.

The internal ground-work may be used in combination with the usual external ground-work or may be used alone and in the latter 15 case the usual vat may be omitted.

In the accompanying drawings are illustrated three examples of construction of the new cylinder machine.

20 Figure 1 is a cross section of the first form of construction.

Figure 2 shows the suspension of the internal ground-work.

25 Figure 3 is a section on the line 3—3 of Figure 2.

Figures 4 and 5 show another form of construction of the internal ground-work in side elevation and plan.

30 Figures 6 and 7 show a second form of construction of the new cylinder machine in cross section and plan.

Figures 8 and 9 show a third form of construction of the new cylinder machine in cross section and plan.

35 In the form of construction according to Figures 1 to 3 the grinding roller 1, to be described hereinafter in detail, is mounted in a usual trough 2 of the usual character having an inclined gutter 3, which in plan is 40 of O-shape and provided with an enlargement 4 over which the pulp is raised towards the right so as to return through the gutter 3 to the left of the grinding roller. The grinding roller co-operates in the usual manner with a ground-work 5 in the bottom of the trough 2.

The grinding tools of the grinding roller consist of metal cutters 6 which in the usual manner are secured in the end walls 7 of the 50 roller. The otherwise usual wood lining between the cutters 6 is in the present case omitted so that the pulp can enter and again pass out through the spaces between the cutters into and out of the interior of the grinding 55 roller.

The grinding roller, rotated in any suitable manner, is mounted at both ends in pivots 8 which are rotatably fitted into eyes 9 of levers 10. The latter are rotatable about 60 fixed pivots 11 and can be rocked on these for example by means of screws 12 so as to adjust the distance of the grinding roller 1 from the ground-work 5.

65 In the interior of the grinding roller is provided a second ground-work 13 which

is pivotally suspended by means of pivots 14 on the arms 15 of a shaft 16. The latter extends through the grinding roller 1 and can be raised and lowered relatively thereto. For this purpose the shaft 16 is, for example, fitted eccentrically and non-rotatably in the supporting pivots 8 of the grinding roller 1 and these pivots are provided with arms 17 with screws 18 in their ends which bear against lateral projections 19 on the levers 10. By turning the screws 18 the internal ground-work 13 can be raised or lowered relatively to the grinding roller 1.

The pulp passes from the lowermost parts of the gutter 3 into the trough 2 partly between the outer side of the grinding roller 1 and the external ground-work 5, and partly through the spaces between the cutters 6 between the inner side of the grinding roller 1 and the internal ground-work 13. After it has passed both ground-works it passes partly over the enlargement 4 into the high portion of the gutter 3 into the portion 2 and flows partly back over the rear side of the internal ground-work 13 so as to be again capable of being ground.

By this arrangement the length of the grinding surface relatively to the total path of the pulp is practically double. To this is also added the return flow of a portion of the pulp over the rear side of the internal ground-work so that for this portion of the pulp a shorter return path is provided and on the whole by reason of the return paths of different lengths an efficient mixing of the pulp is obtained.

In the form of construction according to Figures 6 and 7 the portion 2 is provided with two gutters 3a, 3b which in plan have substantially the form of an 8. Into the 105 spaces between the cutters 6 of the grinding roller 1 are fitted wood wedges 20 beyond which the cutters project inwardly and outwardly. The cutters may, however, be replaced by grinding tools of stone-ware.

The pulp flows to the overflow over the enlargement 4 through the gutter 3a of the trough 2 to one open end of the grinding roller 1 and there passes over a step 21 into the interior thereof. It then passes between the inner surface of the grinding roller 1 and the internal ground-work 13 and passes to the oppositely disposed outlet step, at the other end of the grinding roller 1 which is also open, which is lower than the inlet step 21 into the second gutter 3b of the trough 2 by which it is conducted to the outer side of the grinding roller 1 and the external ground-work 5. During its passage through the grinding roller 1 in the direction of its longitudinal axis the pulp describes a kind of spiral line.

With this arrangement the ratio of the length of the grinding surfaces relatively to the total path of the pulp is further in-

creased as the latter, after once passing through the external ground-work must again during its passage pass repeatedly through grinding surfaces without it being necessary to provide additional grinding rollers in the trough.

In the form of construction according to Figures 8 and 9 an external ground-work is not provided. In this case the pulp again passes in the direction of the longitudinal axis through the grinding roller 1 as in Figures 6 and 7. The trough 2 is provided with two gutters 3c and 3d which are partly superposed and are connected together by a passage 22. For the purpose of overcoming the difference in level between the inlet and outlet there is fitted into the passage 22 a worm or the like, not shown, which raises the pulp from the lower gutter 3d into the upper gutter 3c.

The pulp passes repeatedly between the ground-work 13 and the inner surface of the grinding roller 1 and thus again describes spiral lines.

The cylinder machine according to Figures 8 and 9 can also be used without a trough as it is possible to impart to the spiral path of the pulp only a very slight inclination so that the grinding operation is completed by passing the pulp once through the grinding roller.

In the forms of construction according to Figures 6 and 7 and 8 and 9 the lateral conveying of the pulp in the direction of the axis of the grinding roller 1 can be supported in that, as shown in Figures 4 and 5, ribs 23 are provided on the rear side of the internal ground-work 13, these ribs extending at an angle to the direction of the axis and move the pulp somewhat laterally between two succeeding passages through the grinding surfaces. When the ribs 23 are of sufficient depth it is possible to operate without a difference in level between the inlet and outlet sides and in spite of this to pass the pulp at a constant speed through the grinding roller.

The invention is not limited to the use of cutters as grinding tools, but the grinding surfaces of the grinding roller and/or of the ground-works may also be produced of stone-ware in the manner otherwise usual. In this case the grooves and notches usually provided in the stone-ware may be retained.

We claim:—

1. In a cylinder paper mill for the treatment of raw and semi-raw materials for the production of paper, cardboard, pasteboard and the like the combination with a hollow grinding roller open at its ends, of a ground-work located in the interior of the grinding roller and extending only over a portion of the internal periphery of said grinding roller and grinding tools provided on the inter-

nal surface of said grinding roller for co-operation with said ground-work.

2. In a cylinder paper mill according to claim 1, wherein the grinding tools are in the form of metal cutters or stone-ware.

3. In a cylinder paper mill according to claim 1, a shaft extending through the interior of the grinding roller, means for raising and lowering said shaft relatively to said grinding roller, and arms secured to said shaft, the said ground-work being pivotally suspended from said arms.

4. In a cylinder paper mill according to claim 1, wherein ribs are provided on the rear side of said ground-work, said ribs being inclined to the axis of said grinding roller.

5. In a cylinder paper mill according to claim 1, having means whereby the material to be treated is supplied to one end of the grinding roller and conducted away from the other end of said grinding roller and returned to the first mentioned end without passing outside the grinding roller.

6. In a cylinder paper mill according to claim 1, wherein the roller is mounted in a trough having a gutter therein located at a high level by which the material is conducted into one end of the grinding roller, said trough having a second gutter therein at a lower level which receives the material from the other end of the roller, and means for conveying the material from the low level gutter to the high level gutter.

7. In a cylinder paper mill according to claim 1 in combination with an external ground-work and grinding tools on the outer side of said grinding roller for co-operating with said external ground-work.

8. In a cylinder paper mill according to claim 1 in combination with an external ground-work, and grinding tools on the outer side of said grinding roller for co-operating with said external ground-work, a trough in which said grinding roller is mounted, said grinding roller having spaces between the grinding tools, said trough having a gutter therein of which portions are at different levels, the material to be ground being conducted to the external and internal grinding surfaces of the grinding roller on one side thereof from the portion of the gutter at the low level, and a projection in said trough over which the material is conducted from the other longitudinal side of the grinding roller into the trough of the gutter disposed at a higher level and from which it returns to the portion of the gutter at a lower level.

9. In a cylinder paper mill according to claim 1 in combination with an external ground-work, and grinding tools on the outer side of said grinding roller for co-operating with said external ground-work, a trough in which said grinding roller is mounted, said grinding roller having spaces between the grinding tools, said trough having a gutter

therein of which one portion is disposed at a higher level than the other, the material to be treated being conducted to the outer grinding surface of the grinding roller along one longitudinal side thereof from the portion of the gutter at a lower level, a projection in said trough over which the pulp is conducted from the other longitudinal side of the grinding roller into the portion of the gutter which is at a higher level, is conducted from the last mentioned portion of the gutter to the internal grinding surface of the grinding roller at one end thereof and passes from the other end thereof into the portion of the gutter at a lower level so as to be again returned to the outer grinding surface.

10. In a cylinder paper mill according to claim 1, hollow trunnions secured to opposite ends of said grinding roller, a pair of arms in which said trunnions are mounted, means for adjusting said arms, a trough in which said grinding roller is mounted, an external ground-work in said trough for co-operation with the outer surface of said grinding roller, and a shaft eccentrically mounted in said trunnions, the ground-work located in the interior of the grinding roller being pivotally mounted on said shaft.

15. In testimony whereof we have affixed our
20 signatures.

ULRICH KIRCHNER.
GERALD STRECKER.
